Inventor:
Michael Brayen

UNITED STATES PATENT OFFICE.

MICHAEL BRAYER, OF ROCHESTER, NEW YORK.

MACHINE FOR CUTTING STAVES.

Specification of Letters Patent No. 23,550, dated April 12, 1859.

To all whom it may concern:

Be it known that I, MICHAEL BRAYER, of Rochester, in the county of Monroe and State of New York, have invented a new and Improved Machine for Cutting Staves; and I do hereby declare that the following is a full, clear, and exact description of the same, reference being had to the annexed drawings, making a part of this specification, in which—

Figure 1, is a side sectional view of my invention taken in the line x, x , Fig. 2. Fig. 2, is a plan or top sectional view of do., taken in the line y, y , Fig. 1.

15 Similar letters of reference indicate corresponding parts in the two figures.

This invention relates to an improvement in that class of stave cutting machines in which a knife having a curvilinear movement is employed for cutting the staves in curved form direct from the bolt.

20 The invention consists in the employment or use of levers fitted in the bed of the machine and arranged substantially as hereininafter described, to aid in removing the “waste” or refuse pieces of the bolts from the machine.

To enable those skilled in the art to fully understand and construct my invention, I 30 will proceed to describe it.

A, represents the bed of the machine which is inclined, as shown clearly in Fig. 1, and fitted between side pieces a, a , which are secured on any proper framing. In the 35 inner surfaces of the side pieces a, a , and near their front ends curved grooves b, b , are made, one in each side piece, said grooves forming portions of circles corresponding to the desired transverse curvature of the staves to be cut.

40 B, represents a knife gate which is of cast iron. This gate may be described as being formed of four different parts, two side pieces c, c , each of which is provided at its outer side with a way or guide d , which guides correspond in curvature with the grooves b, b , and are fitted therein. The 45 gate also has a top curved plate e , which forms the bed for a knife f , and a lower plate g , which forms a gage. The inner surface of the lower plate g , is provided

with a series of guides h , which are parallel with each other, and fit in recesses or grooves i , in the front edge of the bed A. To each side piece c , an arm j , is attached, and these 55 arms are provided with journals k , which work in bearings l , attached to the side pieces a, a . The journals k , are at the centers of circles of which the grooves b, b , and ways or guides d, d , form portions. The 60 arms j, j , extend a short distance in front of the gate B, as shown in both figures.

The upper plate or knife bed e , it will be seen curves inward so as to form a throat m , for the knife f , as shown clearly in Fig. 1. 65

In the bed A, two bent levers n, n , are placed. The form of these levers is shown clearly in Fig. 1, and their lower ends below the bed are connected by a cross bar o .

The operation of the machine is as follows:—The bolt, shown in red from which the staves are cut is got out of proper dimensions and placed on the bed A, the bolt feeding itself by its own gravity to the gage g , the inclination of bed A, permitting 70 such result. Power is applied to the outer ends of the arms j, j , in any proper way and a reciprocating motion is given the gate B, the knife f , cutting a stave from the bolt each time it descends. The staves as they 75 are cut pass through the throat m , and each time the knife ascends the bolt descends to the gage g , and assumes a proper position for the succeeding descent of the knife.

The refuse of the bolt is removed from the 80 bed A, by tilting upward the levers n, n , which is done by shoving forward the cross bar o ; this movement of the levers throws the refuse block or waste piece backward 85 from the gate and prevents the possibility of the operator being injured by the knife, the movement of which need not be stopped.

By having the gate B, provided with ways or guides d, d , fitted in grooves b, b , in the side pieces a, a , of the bed A, and by having the guides h , of gage g , fitted in the front end of the bed A, the knife gate is made to operate perfectly true, not liable to be affected by wear as good bearing surfaces are obtained, and any irregular movement 90 is prevented which would otherwise attend a slight wear of the journals k , or bearings l .

I do not claim a reciprocating knife gate working in the arc of a circle for such device has been previously used; but,

Having thus described my invention, what
5 I do claim as new and desire to secure by
Letters Patent, is,

The employment or use of the levers n, n ,

in combination with the inclined bed A, arranged substantially as and for the purpose set forth.

MICHAEL BRAYER.
